(57) **CLAIM**

We claim, the ornamental design for a bottle, as shown and described.

DESCRIPTION

FIG. 1 is a top, front, and left side perspective view of a bottle showing our new design;

FIG. 2 is a top, rear, and right side perspective view thereof;

FIG. 3 is a front elevational view thereof;

FIG. 4 is a top plan view thereof;

FIG. 5 is a left side elevational view thereof, the right side elevational view being a mirror image;

FIG. 6 is a rear elevational view thereof; and,

FIG. 7 is a bottom plan view thereof.

The broken line showing of a portion of the bottom in FIG. 7 is included for the purpose of illustrating environmental structure and forms no part of the claimed design.
